CLAIM

The ornamental design for a vessel with a hook for hanging, as shown and described.

DESCRIPTION

FIG. 1 is a bottom perspective view of a vessel with a hook for hanging;

FIG. 2 is a right view thereof;

FIG. 3 is a left view thereof;

FIG. 4 is a front view thereof;

FIG. 5 is a rear view thereof;

FIG. 6 is a top view thereof; and,

FIG. 7 is a bottom view thereof.

The broken lines showing portions of the vessel with a hook for hanging form no part of the claimed design.

1 Claim, 4 Drawing Sheets
